UNITED STATES PATENT OFFICE

JOHN CARTMELL, OF SPOKANE, WASHINGTON, ASSIGNOR TO THE C. R. C. AIR CLEANER COMPANY, OF SPOKANE, WASHINGTON

AIR CLEANER

Application filed January 26, 1931, Serial No. 511,265.

My invention relates to air cleaners and more particularly to air cleaning devices that are adapted to be connected with motors, compressors and other engines for the purpose of removing the dust from the air before it is taken into the engine. Certain objects of the invention are to provide an air cleaner comprising a one-piece casing with integral inlet and outlet members and an inner casing having a main and arcuate baffle cleaner members detachably mounted therein. Another object of the invention is to curve and space the arcuate baffle members in such manner that the ends of each will overlap the bulging center of the next member whereby the air is compelled to impinge said members in its passage therebetween. Further objects are to provide a detachable bottom pan for the casing having an oil contained sub-chamber with a flanged lid for retarding the escape of air whereby its dust is deposited on the oil. Still further objects are to provide novel baffle members with means for causing a maximum collection of dust and to dispose said members in such manner as to cause a maximum interception of the air passing through the device.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a view in side elevation showing the forward portion of a tractor with my device installed thereon;

Fig. 2 is a view in vertical section of an auxiliary cleaning apparatus that may be connected to the main cleaner;

Fig. 3 is a detail view in perspective of the main cleaner;

Fig. 4 is a view in longitudinal vertical section of the same taken substantially on a broken line 4, 4 of Fig. 3;

Fig. 5 is a detail view in perspective showing a fragmentary portion of one of the baffle cleaner elements; and

Fig. 6 is a detail view in perspective of the

flanged lid for the oil sub-chamber in the bottom pan.

Referring to the drawings throughout which like reference numerals indicate like parts, the numeral 5 designates the main cleaner casing that is made in one piece and is provided with lugs 6 whereby same may be mounted for use in connection with motors and other engines that use air in their combustion or operation. The top portion of said cleaner casing is provided with an integral outlet member 7 and an integral intake member 8. A plurality of slots 9 is provided in the top of said intake as shown in Fig. 3 and for reasons hereinafter set forth.

As shown in Fig. 1 of the drawings, the device is ordinarily interposed in the air intake pipe line and forward of the carburetor with its intake member 8 connected to the intake portion of the pipe that is open to atmospheric pressure and its outlet member 7 connected to the portion of the pipe that leads to the intake manifold of the engine.

A separate inner casing 10 is adapted to fit snugly into the main casing 5. Said inner casing is installed through the open bottom of said main casing and is also provided with an open bottom having a narrow flange 11 around its bottom edge which fits snugly up against the bottom edge of the main casing.

The inner casing 10 has a short baffle 12 slanting downwardly and outwardly or forwardly from its upper rear end which baffle registers with the lower rear end of the intake member 8 in the installed position as clearly shown in Fig. 4 of the drawings. A main baffle member 13, disposed transversely of the inner casing, extends downwardly and rearwardly from the forward end of the intake member to a point adjacent the rear wall of the inner casing thus forming a restricted passage 14 therewith.

A plurality of arcuate baffle members 15, vertically disposed in spaced relation and transversely of the inner casing, extend from the bottom of said inner and main casings to their tops and in communication with the outlet member 7.

A very important feature of my invention

resides in curving and spacing the arcuate baffle members 15 in such manner that the vertical alignment of their tops and bottoms overlap the central or bulging portion of 5 the next baffle. Thus the air passing upwardly between said baffles, which air would ordinarily travel in a straight line, is compelled to impinge their sides as will be understood.

10 The arcuate baffle members 15 may comprise a thick pad of felt or other absorbent material 16 that is preferably saturated with oil. Said pad is held between two plates 17 that are provided with downwardly and 15 outwardly projecting riffles or baffles 18 that may be stamped or punched outwardly from said plates. The lateral edges of said baffle members are held in a groove or channel 19 that is formed by pressing ridges outwardly 20 from the sides of the inner casing 10 as most clearly shown in Fig. 5. The main baffle member 13 is likewise mounted and constructed and its baffles 18 project upwardly instead of downwardly. It will thus be apparent 25 that all of said baffle members may be readily removed and taken apart for the purpose of cleaning.

A bottom pan, designated as a whole by the numeral 20, is provided with an offset flange 30 21 around its top which is adapted to snugly fit the bottom edge of the casing 5 or rather the bottom flange 11 of the inner casing 10. Said pan is held in position on the bottom of said casing by springs 22 that are so tensioned that the pan may be snapped into position as will be understood. A sub-chamber 35 23 may be disposed in the lower rear end of said pan and partly filled with oil or oil soaked cotton waste or the like. Said sub-chamber is provided with an open-top flanged lid 24 as shown in detail in Fig. 6. The flanges of said lid are adapted to retard the escape of air projected into the sub-chamber so that it may deposit its dust on the oil or 40 45 fabric. Loose or floating oil may be placed in the main bottom pan, as shown in Fig. 4, for collecting some of the dust from the air.

At each suction stroke of the engine to which the device is connected outside air will 50 be drawn in through the intake member 8 and will take a course through the device somewhat as indicated by the direction arrows shown in Fig. 4. The air will enter both through the main port of said intake 55 member and through its slots 9 which will cause the air to be somewhat broken up or diffused upon its entry. The small baffle 12 will direct the air against the main slanting baffle member 13 whose riffles or baffles 18 will catch and retard the air sufficiently for 60 the oil soaked pad 16 of said main baffle member to collect, by adherence, much of the dust therefrom.

Upon continuing downwardly the velocity 65 of the air will be increased by passing through

the restricted passage 14 which will serve to project the air downwardly into the sub-chamber 23. The flanges of the open-top lid 24 will retard the upward escape of the air from said sub-chamber whereby more of its dust will adhere to its contained oil or oil soaked fabric. Upon rebounding upwardly from the sub-chamber the air will form an eddy due to the down coming air and the space 25 between the main baffle member 13 70 and the first or adjacent arcuate baffle member 15. In this eddy movement some of the air will strike the floating oil in the bottom pan 20 whereby some more of its dust will be deposited. From said pan the air will pass 80 upwardly between the arcuate baffle members and outwardly through the outlet member 7 to the engine. The hereinbefore described overlapping disposition of said arcuate baffles, whereby the air is compelled to impinge their 85 sides together with the retardation of the air by the riffles or baffles 18 of said arcuate members causing the remaining dust to be deposited on their oil saturated felt pads, will complete the cleaning process.

Referring to Fig. 2 of the drawings, I sometimes provide an auxiliary or additional cleaning apparatus in the form of a T-connection 26 for the air intake pipe and in this case the slots 9 of the intake member 8 are 90 eliminated. The pipe joining said T-connection with the main cleaner device is connected to said intake member by means of lugs 27. An inner casing 28 is installed through the bottom of said T-connection and is filled with 100 steel wool, horse hair or the like that is provided with a wire screen 29 at both its top and bottom. A bottom member 30 is secured to the underside of said T-connection by bolts 31 and it will thus be seen that the inner 105 casing and its filler may be readily removed for cleaning. In the use of this auxiliary cleaning apparatus the air is drawn thereinto, prior to its entry into the main cleaner, and strikes against the absorbent material 110 whereby some of the dust adheres thereto as the air rebounds in its passage into the intake member 8.

Having thus described my invention, it being understood that minor changes may be 115 resorted to in its construction and arrangement without departing from the scope and spirit of the invention, what I claim and desire to secure by Letters Patent of the United States is:—

1. An air cleaner having in combination a one-piece main casing, integral intake and outlet members for the casing top, said intake member having a plurality of slots arranged to diffuse the air entering its port, 125 an inner casing fitting snugly into the main casing and adapted to be installed through the open bottom thereof, a main baffle member disposed transversely of the inner casing slanting rearwardly from the inlet to 130

- form a restricted passage between its bottom edge and the rear wall of said inner casing, a small baffle arranged to direct entering air against said main baffle, a pan 5 detachably secured to the bottom of the casings, a sub-chamber for the pan having oil or oil-soaked filler therein and disposed directly below the restricted passage, an open-top flanged lid for the sub-chamber, a plurality of arcuate baffle members vertically disposed transversely of the inner casing in communication with the outlet member. 10 In testimony whereof I affix my signature.
JOHN CARTMELL. 70
- 75
- 15 lap the central bulges of adjacent baffles, absorbent oil saturated fabric pads for the arcuate and main baffle members, metal plates for said pads, ruffles punched outward from said plates in directions slantingly adapted to intercept the passage of air 20 through the casing and grooves in the side walls of the inner casing for detachably receiving the lateral edges of said baffle members. 25 An air cleaner having in combination a one-piece main casing, integral intake and outlet members for the casing top, an inner casing adapted to be installed through the open bottom of the main casing, a main baffle 30 member slanting rearwardly from the intake to form a restricted passage with the inner casing, a small baffle arranged to direct entering air against the main baffle, a pan detachably secured to the bottom of the casings, 35 a sub-chamber disposed directly below the restricted passage, an open-top flanged lid for the sub-chamber, a plurality of arcuate baffle members vertically disposed transversely of the inner casing in communication with the outlet member, projecting ruffles and oil 40 saturated pads for the arcuate and main baffle members, and said arcuate baffles curved and spaced in such manner that their end alignments vertically overlap the central bulges 45 of adjacent baffles. 3. An air cleaner having in combination a main casing, intake and outlet members for said casing, an inner casing for the main casing, a detachable main baffle member slanting rearwardly from the intake to form a restricted passage, a small baffle arranged to direct incoming air against the main baffle, a pan detachably secured to the bottom of the casings, a sub-chamber disposed below the restricted passage, an open-top flanged lid for the sub-chamber, and a plurality of arcuate baffle members transversely disposed of the inner casing and in communication with the outlet member. 50 4. An air cleaner having in combination a main casing, intake and outlet members for said casing, an inner casing, a main baffle member adapted to form a restricted passage, a detachable pan for the bottom of the casings, a sub-chamber for said pan, and a plu- 55 60 65 70 75 80 85 90 95 100 105 110 115 120 125 130
